[57] CLAIM

The ornamental design for a circulating air cleaner or the like, substantially as shown and described.

DESCRIPTION

FIG. 1 is a top and front perspective view of a circulating air cleaner or the like showing our new design, the bottom being substantially similar in appearance; FIG. 2 is a left side elevational view thereof, the right side being a mirror image and the cord element shown broken away to indicate indeterminate length; and FIG. 3 is a rear elevational view thereof.

Fig. 1
